CONTROL MECHANISM FOR VARIABLE SPEED MECHANISM

Harry C. Clay, Columbus, Ind., assignor to Reeves Pulley Company, Columbus, Ind., a corporation of Indiana

Original application April 8, 1935, Serial No. 15,209. Divided and this application December 15, 1939, Serial No. 309,307

3 Claims. (Cl. 74—1)

The present invention relates to a control means for a driven machine such, for instance, as a so-called woolen spinning frame, whereby the speed of the spinning frame is automatically controlled directly in accordance with the demands of such spinning frame, and with a sensitivity far beyond any heretofore attainable. Further objects of the invention will appear as the description proceeds.

This application is a division of my co-pending application, Serial No. 15,209, filed April 8, 1935, upon which issued Patent No. 2,225,952, December 24, 1940.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a broken diagrammatic view of a woolen frame having associated therewith a hydraulic controlling mechanism constructed in accordance with the present invention;

Fig. 2 is an idealized diagram of the manner in which the yarn is wound on each bobbin spindle of the frame;

Fig. 3 is a broken isometric view of such a hydraulic control associated with a variable speed power transmission mounted to drive such a spinning frame; and

Fig. 4 is a sectional view of the control.

Referring more particularly to the drawings, it will be seen that I have illustrated a machine comprising a frame 10 upon which are suitably mounted to be rotated a series of spindles 11 upon which the yarn 12 is to be wound. The machine of course includes a suitable "builder motion" (not shown) suitably driven by the main shaft of the machine, and operating to drive the ring rail 14 of the machine. It may be noted here that, in some types of machines, the ring rail itself is reciprocated with respect to the spindles 11; whereas in other types of machines the spindles are reciprocated with respect to the stationary ring rail; and it will be obvious that the two types of machines are equivalent in that they accomplish the same result in substantially the same way. In either case, the relative reciprocation between the ring rail and the spindles is effected by operation of the "builder motion."

A lever 15 is oscillably mounted on a stub shaft 13 and carries at one end a counter-balance 16, while at the other end said lever 15 is connected

10 through a yoke 17 to one arm 18 of a bell crank lever 19. Suitable means, such as a cam, is provided whereby operation of the "builder motion" causes oscillation of the lever 15. To the other arm 20 of the bell crank lever 19 is attached a yoke 21 adjustably carried at one end of an elongated rod 22 guided on and supported by a series of rollers 23; the opposite end of said rod 22 carrying a second yoke 24 connected to one arm 25 of a second bell crank lever 26. To the opposite arm 27 of said bell crank lever 26 is connected a yoke 28 attached to a cable 29 which runs over a roller 30 and under a roller 31, terminating in a yoke 32 attached to one end of an arm 33 pivoted at 34 on a standard 35. The standard 35 is carried by the core 36 of a solenoid indicated at 37.

15 The lever 33 is provided with an extension 38 connected to said lever 33 through the medium of a strain relieving joint 39; and said extension 38 is urged constantly downwardly by a spring 40. The free end of the extension 38 is operatively connected to a rod 41 which is a part of the control per se housed within the casing 42.

20 At 43 and 44 I have indicated a source of electrical energy, such as a pair of line wires, said line wires being connected by leads 45 and 46 to a switch box 47. Two leads 48 and 49 provide an energizing circuit, controlled by a switch in the box 47, for the solenoid 37; and two leads 50 and 51 provide an energizing circuit, controlled by a switch in the box 47, for a pilot motor 52 carried on the casing 42. An arm 53, having branched fingers 54 and 55, controls the switches in the box 47.

25 A coned disc 56 is rigidly mounted on the main shaft (not shown) of the spinning frame; and a second coned disc 57 is mounted coaxially therewith, said disc 57 being axially movable and being constantly urged toward the disc 56 by a spring 58. Obviously, the discs 56 and 57 cooperate to form an expansible V-pulley; and a belt 59 of V-cross section provides a driving connection between said pulley and a driving pulley 30 comprising cones 60 and 61 mounted upon the spindle 62 of a motor 63. The discs 60 and 61 are preferably axially fixed with respect to each other. The motor 63 is mounted upon a bed plate 64 which is reciprocable in a guide way formed in a base 65. It will be obvious that, as the motor 63 moves downwardly, the belt 59 will be pulled more deeply into the crotch between the discs 56 and 57, thereby separating the said discs; and, as the motor 63 moves upwardly the belt 59 will be forced outwardly by the tend-

ency of the disc 57 to approach the disc 56 under the influence of the spring 58. It follows that, as the motor 63 moves downwardly the speed of the spinning frame will be increased, and as the motor 63 moves upwardly, the speed of the spinning frame will be decreased.

The rod 41 is connected at its upper end, through a bracket 66, to the upper end of a rod 67 extending into the interior of the casing 42 and connected, at its lower end, through a bracket 68, with a valve member 69. The motor 52 carries, within the casing 42, a sprocket 70 which drives, through a chain 71, a sprocket 72 on the shaft of a pump 73 which is operable to draw liquid from within the casing 42 through the inlet pipe 74, and to discharge it through the outlet pipe 75. Said outlet pipe is connected to a casing 76 providing a chamber 77, said casing 76 being formed with a flange 78 at one end, and said flange being positioned to close one end of a fluid motor cylinder 79. The opposite end of said cylinder is closed by a cap 80; and a piston 81 is reciprocable within said cylinder. A stem 82 projects upwardly from said piston 81, being integral therewith, and said piston is further formed with a downward extension 83, likewise integral therewith. The stem 82 projects outwardly through the cap 80 and, at its upper end, receives a pin 84 through which a cross member 85 is connected to said stem 82, said cross member 85 carrying straps 86 connected to ears 87 on the motor 63. It will be obvious that this arrangement provides a connection between the piston 81 and the motor 63 which will cause the motor 63 to follow accurately all movements of the piston 81.

The extension 83, the piston 81, and a portion of the stem 82 are axially bored to provide a socket 88 in which is mounted the upper end of the valve member 69, said valve member being reciprocable in said socket. A port 89 opens outwardly through said socket immediately above the upper surface of the piston 81, and a second port 90, preferably diametrically opposed to the port 89, likewise opens outwardly from the socket 88 immediately above the upper surface of the piston 81. A port 91 opens from one side of the socket 88 immediately below the lower surface of the piston 81, and a port 92 opens from the other side of said socket, immediately below the lower surface of the piston 81.

As is clearly shown in Fig. 4, the valve member 69 is formed to provide a passage 93, closed at its lower end by a plug 94, and provided with three ports, 95, 96, and 101 opening through the outer wall of the valve member 69. Said ports 95 and 96 are positioned within the socket 88 and are spaced apart a distance slightly greater than the distance between the ports 89 and 92; while the port 101 is positioned within the chamber 77. Said valve member is further formed to provide a second passage 97, open at its lower end 98, and provided with a pair of ports 99 and 100 opening through the outer wall of said valve member. Said ports 99 and 100 are spaced apart a distance slightly less than the distance between the ports 90 and 91.

It is to be understood that the casing 42 will be filled with liquid to a level above the lower end of the pipe 74. If the pump 73 is in operation, the chamber 77 will be always full of liquid under pressure, it being understood that a relief valve (not shown) is provided between the pump 73 and the chamber 77. With the parts in the positions illustrated in Fig. 4, no liquid

can flow from the chamber 77 into the cylinder 79, nor can liquid flow from the cylinder 79 into the sump in the casing 42. However, if the rod 41 is moved slightly upwardly, the port 96 will be brought into registry with the port 92; and the port 99 will be brought into registry with the port 90. Liquid under pressure from the pump 73 will thereupon be supplied through the pipe 75 to the chamber 77, through the port 101 into the passage 93, and thence through the ports 96 and 92 to that portion of the cylinder 79 below the piston 81. Thereby, the piston 81 will be moved upwardly. Since the ports 99 and 90 are in registry, such upward movement of the piston 81 forces liquid from above the piston 81 through the ports 90 and 99 and the passage 97 into the sump in the casing 42. If the initial upward movement of the rod 41 is discontinued, such upward movement of the piston 81 will almost immediately move the ports 92 and 96 out of registry with the respective ports 96 and 99, and the system will again come into equilibrium.

Obviously, downward movement of the rod 41 will move the valve member 69 to bring the ports 95 and 100 into registry with the ports 89 and 91, respectively, whereby liquid will be supplied to the upper portion of the cylinder and exhausted from the lower portion of the cylinder 79, the piston 81 thereby being moved downwardly until the ports 89 and 91 again move out of registry with the ports 95 and 100.

The sensitivity of the disclosed system is remarkably high; and at least some of that sensitivity is, in my opinion, due to the fact that the port centers are so positioned that the ports 95 and 96 slightly overlap the ports 89 and 92 when the organization is in a condition of equilibrium.

Upon reference to Fig. 1, it will be seen that, with the parts in the positions illustrated, the cable 29 is so slack that oscillation of the lever 15 will not affect the lever 33. This condition of slackness is maintained by energization of the solenoid 37 to hold the core 36 and standard 35 down in the position illustrated. During the operation of the spinning frame, the ring rail 14 reciprocates through a relatively short path, each upward stroke of the ring rail being slightly longer than the following downward stroke thereof; whereby the path of reciprocation of the ring rail moves gradually upward, step by step. With the arm 53 in the position illustrated, the leads 48 and 49 are energized to supply current to the solenoid 37; but the leads 50 and 51 are deenergized, so that the motor 52 is not in operation. Consequently, the machine operates at a constant predetermined speed until such time as the ring rail 14 engages the finger 54 of the lever 53 to rotate said lever slightly in a clockwise direction; whereby the circuit including the leads 48 and 49 is broken and the circuit including the leads 50 and 51 is closed. Springs means (not shown) promptly elevates the core 36 and standard 35 upon deenergization of the solenoid 37, thereby taking up the slack in the cable 29, whereafter every movement of the lever 15 is followed by the lever 33, and consequently the rod 41 and valve member 69. Thus, as the counterweight 16 moves downwardly, the lever 33 is rotated in a counterclockwise direction to elevate the rod 41 and valve 69, whereupon the piston 81 is likewise moved upwardly, carrying with it the motor 63, whereby the operating speed of the spinning frame is decreased. Similarly, upon upward movement of the counterweight 16,

the lever 33 is permitted to move in a clockwise direction under the influence of the spring 40 to depress the rod 41, whereby the piston 81 is moved downwardly. The motor 63 follows such movement of the piston to increase the operating speed of the spinning frame. This operation is continued, the speed of the spinning frame increasing each time the ring rail 14 moves upwardly and decreasing each time the ring rail 14 moves downwardly, until the winding operation is completed. As the operator doffs his spindles, he moves his ring rail 14 downwardly to starting position; and as said ring rail approaches said starting position it strikes the finger 55 of the arm 53 to return said arm 53 to the position illustrated in Fig. 1, whereby the motor 52 is stopped and the standard 35 is again moved to the position of Fig. 1, wherein the cable 29 is slack.

I claim as my invention:

1. In combination, a driven machine including an element reciprocable through a stroke of varying position, power means, a variable speed transmission connecting said power means to drive said machine, a control unit connected to control the speed ratio of said transmission, and including an element shiftable to operate said control, means providing an operative connection between said machine element and said control element, and means for rendering said machine element ineffective to shift said control element.

2. In combination, a driven machine including an element reciprocable through a stroke of vary-

ing position, power means, a variable speed transmission connecting said power means to drive said machine, a control unit connected to control the speed ratio of said transmission, and including an element shiftable to operate said control, means providing an operative connection between said machine element and said control element, and means operable by said machine element in response to variations in the position of the stroke of said machine element for rendering said machine element at times effective to shift said control element and at times ineffective to shift said control element.

3. In combination, a driven machine including an element reciprocable through a stroke of varying position, power means, a variable speed transmission connecting said power means to drive said machine, a control unit connected to control the speed ratio of said transmission, and including an element shiftable to operate said control, means providing an operative connection between said machine element and said control element, electrical means operable, upon energization, to render said machine element ineffective to shift said control element, a circuit for energizing said electrical means, a switch in said circuit, and an operating member for said switch located in the path of said machine element and engageable thereby, the position of said switch operating member being dependent upon the position of the stroke of said machine element.

HARRY C. CLAY.
